UNITED STATES PATENT OFFICE.

DAVID KNOX, OF LYNN, MASSACHUSETTS.

LEATHER-CUTTING MACHINE.

SPECIFICATION forming part of Letters Patent No. 317,463, dated May 5, 1885.

Application filed February 24, 1885. (No model.)

To all whom it may concern:

Be it known that I, DAVID KNOX, of Lynn, in the county of Essex and State of Massachusetts, have invented certain Improvements 5 in Leather-Cutting Machines, of which the following is a specification.

This invention relates to that class of leather-cutting machines in which two vibrating knives are caused to descend alternately on a 10 piece of leather, the knives being reversely curved, so that by their joint action they will cut the leather into sole-shaped pieces without waste, the leather being moved forward after the action of each knife upon it.

15 The invention consists in the improvements hereinafter described and claimed.

Of the accompanying drawings, forming a part of this specification, Figure 1 represents a perspective view of a machine provided with 20 my improvements. Figs. 2, 3, and 4 represent perspective views of parts of the machine detached.

The same letters of reference indicate the 25 same parts in all the figures.

In the drawings, *a* represents the frame of the machine, having a bed, *b*, on which the leather to be cut is supported, the part *b'* of 30 the bed, which is directly under the cutting-knives, being a block of wood. *c d* represent the cutting-knives, which are secured, respectively, to oscillating frames *g h*, pivoted to the frame *a*, and capable of oscillating so as to cause the cutting-edges of the knives to alternately approach and recede from the block *b'*.

35 The frames *g h* are arranged so that the knives in oscillating will not interfere with each other, this arrangement requiring the knife *d* to strike the cutting-block *b'* at behind the point where the knife *c* strikes it.

40 *i i* and *j j* represent rods, which are eccentrically connected to disks *l m* on the ends of two positively-rotated arbors, *o p*, journaled in the lower portion of the frame *a*, said rods being pivoted to the swinging ends of the 45 frames *g h*, and so arranged that when the arbors *o p* are rotated the frames *g h* will be oscillated simultaneously in opposite directions, so that the knives are caused to descend upon the bed or cutting-block *b'* alternately, one 50 rising while the other is falling.

The knives are reversely curved, so that each forms one edge of a sole-blank, *r*, the

piece of leather being moved forward by the operator after each cut, so that the next cut forms the opposite edge of the sole, the leather 55 being thus cut without waste.

s s' represent adjustable stops or gages which limit the forward movement of the leather. Said stops are supported by studs *t t*, which are adapted to slide on guides *u u* on a cross-bar, *v*, attached to the frame *a*, and are connected at their outer ends by a yoke, *w*, in which is swiveled a stem, *x*, having a threaded portion working in an internally-threaded socket in the cross-bar *v*. Said stem has a 60 hand-wheel, *y*, whereby it may be rotated to simultaneously move the studs *t t* and stops *s s'* toward or from the cutting-block, and thus regulate the width of the soles. One of the studs is attached to the yoke *w* by a set-screw, 70 *z*, which permits it to be adjusted lengthwise independently, so that its stop can stand in advance of the other stop, thus enabling one stop to act on the edge formed by the knife *c*, and the other on the edge formed by the knife *d*, the 75 former being somewhat in advance of the latter, so that the two knives will not interfere with each other in their operation, as above described. The independent adjustability of the stops enables them to conform to any slight 80 variations in the curvature of the knives which may be caused by their springing. Each stop acts on the projecting convex curve of the sole-edge, so that when the stop *s* is 85 acting to hold the leather the other stop, *s'*, is opposite the concave curve of the sole-edge and does not touch the latter. When the next edge is presented, the convex curve is presented to the stop *s'* and the concave curve is opposite the stop *s*. The stops *s s'* are provided 90 with upwardly-projecting curved plates or guards *a' a'*, which are bent downwardly and backwardly at their upper ends, and prevent the soles and pieces of leather from accidentally passing over the stops and resting on the 95 studs *t t*.

b² represents an incline affixed to the frame *a* to guide the severed soles downwardly.

c' represents a rock-shaft journaled in the frame *a* over said incline and provided with 100 two arms, *d' d'*, which project over the forward edge of the sheet or piece of leather, and are oscillated by the shaft *c'*, so as to knock each sole downwardly onto the incline *b²* as soon as

it is severed, so that the sole that is severed shall not interfere with the sole that is next to be severed. These arms are arranged to strike the sole near its opposite ends, and thus 5 effectually push or knock it downwardly. The arms are preferably provided with movable sections d^2 at their outer ends, which are adjustable by means of set-screws and slots, so that the length of each arm may be varied. 10 The arms d^1 d^2 are secured to the rock-shaft c' by set-screws u' u' , which enable said arms to be set at any desired distance apart, so as to accommodate them to soles of different length, and also to be set at any desired angle on the 15 shaft, so that the time of their descent upon the soles may be accurately adjusted. Heretofore in machines of this class a single knocker-arm has been employed, which, striking the sole at one point only, does not knock it down 20 as promptly and efficiently as the two arms here shown, and sometimes causes one end of the sole to tip upwardly and be caught between the end of the piece of leather awaiting the next cut and the stop which arrests the 25 leather, thus preventing the leather from reaching the stop, and therefore causing the next sole to be of insufficient width. Moreover, the single arm heretofore used has not been made adjustable on its rock-shaft, so that 30 in case it became bent or sprung it could not be easily adjusted to properly time its operation. The rock-shaft c' is provided with an arm, f' , at one end, to which is pivoted a rod, g' , the other end of which is eccentrically 35 pivoted to a disk, h' , on a shaft, i' , journaled in the lower portion of the frame. The rotation of said shaft oscillates the rock-shaft c' and its arms d^1 d^2 . The shaft i' is provided with a pulley, k' , on which the driving-belt 40 runs. Said shaft is also provided with a gear, l' , which meshes with gears m' m' on the shafts o p and rotates the same. These gears are located within the frame a , and under the bed b and inclined bed b^2 , so that they are out of 45 the way and cannot be clogged or obstructed by scraps or pieces of leather that may fall from the machine.

I claim—

1. In a leather-cutting machine in which are 50 combined a cutting-block, the alternately-operating curved knives, the pivoted frames carrying said knives, arranged to permit the

knives to strike the bed at different points, the mechanism for oscillating said frames simultaneously in opposite directions, and two stops or gages arranged the one in advance of the other, to permit the knives to act at different points on the bed, the curved guards a' a' , secured to said stops, whereby the soles and pieces of leather are prevented from passing 60 over the stops, as set forth. 55

2. In a leather-cutting machine, the combination, with the cutting mechanism, of the stops having the curved guards, as set forth.

3. The combination, with the cutting-block 65 and the alternately-operating knives, of the two stops or gages having the guards a' a' , the studs t t , the cross-bar v , supporting said studs, the yoke connecting the studs and detachably connected to one of the studs, to 70 permit its independent adjustment, and the screw swiveled in said yoke and working in a threaded socket in the cross-bar, as set forth.

4. The adjustable stops having the plates or guards a' a' , combined with the alternately-operating knives and the cutting-block, as set 75 forth. 70

5. The combination, with the knives, cutting-block, and stops, of the two arms or knockers and the mechanism for operating them, as set 80 forth. 80

6. The combination, with the knives, cutting-block, and stops, of the two arms or knockers, the mechanism for operating them, and the devices whereby said arms may be adjusted 85 to vary the distance between them and to time their operation, as set forth. 95

7. In a leather-cutting machine, the combination, with the cutting mechanism, of a rock-shaft having two knocking-arms adjustable 90 thereon, as set forth.

8. In a leather-cutting machine, a rock-shaft having two knocking arms adjustable thereon, as set forth, and provided with the adjustable end sections.

In testimony whereof I have signed my name to this specification, in the presence of two subscribing witnesses, this 18th day of February, 1885.

DAVID KNOX.
